TRITURATING DEVICE.

1,124,442.

Specification of Letters Patent.

Patented Jan. 12, 1915.

Application filed June 9, 1911. Serial No. 632,235.

To all whom it may concern:

Be it known that we, FRANK K. HOOVER and ARTHUR J. MASON, citizens of the United States, residing at Chicago, in the county of Cook and State of Illinois, have invented 5 certain new and useful Improvements in Triturating Devices, of which the following is a specification.

This invention relates to improvements in 10 apparatus for treating natural deposits of phosphate rock and other minerals in a natural state for the purpose of freeing the same from clay, iron, and any other foreign matter with which the phosphate of lime or 15 other mineral may be associated in its natural state, thus enhancing its commercial value as a fertilizing or other agent.

The present method of treating phosphate rock, wherein a high grade is desired, consists 20 mainly in roughly washing the larger lumps or pieces only to obtain the desired grade, discarding the smaller and finer particles which are more or less intermixed with clay, iron, sand and like foreign matter more 25 or less adhering to the particles of phosphate of lime.

We have found from extensive work on a considerable variety of the brown rock of Tennessee that the smaller and finer constituent, if properly and thoroughly cleaned 30 and freed from such foreign matter, will return nearly the same percentage of phosphate of lime as the selected larger pieces; and our present invention relates to a device 35 intended for use in a preliminary preparation of the material for the washing out of such foreign matter, and to facilitate the latter operation.

We have found that the cleaning of phosphate rock is most efficiently effected in two 40 stages. The first consists of the softening of the clay, and the second of its separation from the rock; and these two stages of operations are best performed separately. 45 The first, namely, the softening of the clay, is best effected in the presence of a relatively small amount of water; whereas the second operation, consisting of the separation of the clay from the phosphate rock is 50 most efficiently performed in the presence of a relatively large amount of water.

The subject-matter of the present application relates to a novel device for effecting the first of the above-named operations. 55 This device, to which we apply the designation of a mulcher, has for its function to

effect a softening and loosening of the clay and iron which naturally tends to adhere to the particles of phosphate of lime, so that such clay and iron may be more easily 60 brought into solution and suspension in the body of water in which the material is subsequently washed, on very much the same principle as that underlying the rubbing of one's hands with soap to loosen and release 65 the dirt thereon in the operation of washing the hands. The apparatus which we have devised for this purpose, and which constitutes the subject matter of the present invention, operates on this principle of effecting an intimate rubbing or attrition of 70 the particles against each other while the material is in a stiffly plastic state without grinding or disruption of the particles of phosphate rock; and, in its simplest form, 75 it comprises as its chief essential elements an open-ended container made up of a series of superposed horizontal stationary and rotary ring-shaped holders, mounted, preferably, in over-lapping relation, through 80 which the material treated gradually descends upon an underlying support, from the edge of which latter it is gradually scraped off and passed on to the washing apparatus. The effect of the apparatus is to 85 practically sub-divide the total body of material contained therein at any given instant into alternating stationary and rotating strata which are rubbed against each other as the material gradually descends 90 from a stationary holder into a rotary holder and vice versa, thus effecting a very intimate and thorough attrition of all of the particles upon each other, which effectually loosens and softens the clay and other 95 foreign matter from the particles of phosphate rock and places them in a condition to be readily taken up and dissolved by the water in the subsequent washing operation.

The invention, its principle of operation, 100 and the benefits and advantages secured thereby will be readily understood from a consideration of the apparatus illustrated in the accompanying drawings, in which the figure is a central vertical section through 105 the apparatus, showing the material treated in one side of the view.

Referring to the drawing, 5 designates each of a series of superposed spaced rectangular supporting frames, on and within which are 110 supported a series of stationary annular holders 6 secured by bolts 7 passing through

said frame 5 and lateral lugs 8 formed on the upper edges of said holders. Journalized in a top cross-bar 9 and a step-bearing 10 below the frames 5 is a vertical shaft 11, 5 keyed to which are the hubs 12 of a corresponding series of similar rotatable annular holders 13 arranged in alternating relation with the stationary holders 6. The peripheral portions of both series of holders 10 are connected to their hubs by spokes 6^a and 13^a, respectively, and are preferably made tapering or frusto-conical in form, with the narrower lower annular end of each holder internally over-lapping the wider upper end 15 of the next under-lying holder. To prevent the material treated from packing in between the shaft 11 and the hubs of the several holders, and to cause the material to work outwardly or toward the peripheries of the 20 holders where the rubbing action is greatest, guard plates 14 are interposed above the hubs of the stationary holders.

Keyed on the shaft 11 below the series of ring shaped holders is a circular plate 15 on which the material is deposited from the 25 lowermost holder; said plate being provided on its lower side with a bevel gear 16 engaged by a bevel pinion 17 on the inner end of a driving shaft 18, this latter being 30 mounted in journals 19 and driven from any suitable source of power. To effect the gradual and continuous delivery of the material from the supporting plate 15 we provide a displacer in the nature of a stationary plow or scraper 22, engaging the outer edge 35 portion of the plate 15 and deflecting the material off the edge of said plate as it piles up on the latter. In order to bring the material to the proper consistency, which is 40 preferably a plastic state slightly stiffer than ordinary mortar as used in plastering buildings, a small stream of water is introduced at the top of the container through a pipe 23.

45 In the operation of the apparatus, the phosphate rock as it comes from the mine, and preferably previously passed through crushing rolls to reduce it to particles not exceeding one-half inch or thereabouts in size, is delivered into the upper end of the apparatus until the latter is completely filled with such material resting upon the supporting plate 15. Upon a slow motion being 50 imparted to the plate 15 and the several rotary rings or holders 13, it will be evident that the material contained in the rings 13 will revolve while that contained in the alternate rings 6 will not revolve. There is thus produced between the contiguous strata of material contained in the stationary and revolving rings, respectively, an action somewhat similar to that existing 55 between the upper and nether mill stones of a mill. That is, at each point of contact the material is rubbing and polishing itself one

part upon another; and the greater the number of rings and the longer the period of time the material is passing through the apparatus, the more complete this rubbing or polishing action will be. The material is fed in at the top of the container in 70 constant and uniform quantities and at a rate equal to the rate of discharge; and the practical effect of the action of the apparatus on the material is to thoroughly loosen and soften 75 up the clay and other foreign matter and bring it into a condition in which it is readily separated from the mineral particles by the action of water, and brought into solution or suspension in the latter. As the material is constantly descending at a uniform rate through the container, this rubbing and 80 polishing action takes place throughout the entire body of material. We have found that by subjecting phosphate rock to this 85 preliminary mulching treatment before washing the same, the grade is brought up in the neighborhood of three points, as compared with similar material which is washed without such preliminary treatment; that is, 90 rock which would be marketed at 75% B. P. L. (bone phosphate of lime) will grade 78% when subjected to this treatment. It will be obvious that if the rings or holders 95 6 and 13 are revolved in opposite directions the same result will be obtained.

We claim:

1. An apparatus for the purpose described, comprising the combination of a series of concentrically arranged superposed 100 spider members having annular containing flanges, a second series of annular members similarly arranged alternately with respect to said first named members, provided with inwardly projecting arms and forming with 105 the first named members a circular space for the passage of material to be pulverized, and means for effecting relatively rotary movement of said series of annular members.

2. In an apparatus of the character described, the combination of a pair of relatively stationary annular members, spaced apart, superposed and concentrically arranged and each provided with a plurality 110 of beater arms extending toward the center, a relatively movable annular member concentrically arranged with respect to and interposed between and overlapping said first two members and similarly provided 115 with a plurality of beater arms interposed between the beater arms of said first two members, and means for effecting relative rotary movement of the latter annular members with respect to said first two annular members.

3. An apparatus for the purpose described, comprising in combination a series of superposed horizontal stationary and rotary annular holders alternately arranged 120

110

115

120

125

130

in overlapping relation through both of which the material treated descends, a supporting plate for the material beneath said holders, means for effecting rotation of said rotary holders and supporting plate, and a displacer adapted to deflect the material off the edge of said supporting plate, substantially as described.

4. An apparatus for the purpose described comprising in combination a series of superposed stationary supports, a vertical shaft rotatably mounted coincidently with the vertical axis of said supports, a series of ring-shaped holders secured peripherally to said supports, a series of similar rotary holders keyed to said shaft and alternating with said stationary holders, a supporting plate keyed to said shaft beneath said series of holders, means for rotating said shaft, and a stationary displacer adapted to deflect the material off the edge of said supporting plate, substantially as described.

5. In apparatus of the character described, the combination of a series of cone-shaped annular members, spaced apart, concentrically arranged and superposed with respect to each other, a second series of an-

nular members similarly arranged alternately with respect to said first named members with their lower edges overlapping and of a less diameter than the upper edges of said first named members, and their upper edges overlapping and of a greater diameter than the lower edges of said first named members, the members of both series being provided with inwardly extending beater arms and means for effecting relative rotary movement of the two series of annular members.

6. In apparatus of the character described, the combination of a plurality of concentrically arranged, superposed annular members provided with inwardly extending beater arms and internested together in overlapping relation, said members being alternately connected together to form two groups, and means for effecting relative rotary movement of each of said groups.
